(57) **CLAIM**

The ornamental design for a product display and dispensing device, as shown and described.

DESCRIPTION

FIG. 1 is a left perspective view of a product display and dispensing device of the present invention;

FIG. 2 is a front elevational view of the product display and dispensing device of FIG. 1;

FIG. 3 is a left side view of the product display and dispensing device of FIG. 1, the right side view being similar thereto;

FIG. 4 is a rear elevational view of the product display and dispensing device of FIG. 1;

FIG. 5 is a top plan view of the product display and dispensing device of FIG. 1;

FIG. 6 is a bottom plan view of the product display and dispensing device of FIG. 1;

FIG. 7 is a left perspective view of a second embodiment of the product display and dispensing device of FIG. 1;

FIG. 8 is a front elevational view of the product display and dispensing device of FIG. 7;

FIG. 9 is a left side view of the product display and dispensing device of FIG. 7, the right side view being similar thereto;

FIG. 10 is a rear elevational view of the product display and dispensing device of FIG. 7;

FIG. 11 is a top plan view of the product display and dispensing device of FIG. 7;

FIG. 12 is a bottom plan view of the product display and dispensing device of FIG. 7;

FIG. 13 is a left perspective view of a third embodiment of the product display and dispensing device of FIG. 1;

FIG. 14 is a front elevational view of the product display and dispensing device of FIG. 13;

FIG. 15 is a bottom plan view of the product display and dispensing device of FIG. 13;

The left and right side views, the rear elevational view, and the top plan view of the third embodiment, being similar to FIGS. 3, 4, and 5, respectively;

FIG. 16 is a left perspective view of a fourth embodiment of the product display and dispensing device of FIG. 1;

FIG. 17 is a front elevational view of the product display and dispensing device of FIG. 16;

FIG. 18 is a left side view of the product display and dispensing device of FIG. 16, the right side view being similar thereto;

FIG. 19 is a front elevational view of the product display and dispensing device of FIG. 16;

FIG. 20 is a top plan view of the product display and dispensing device of FIG. 16; and,

FIG. 21 is a bottom plan view of the product display and dispensing device of FIG. 16.

The matter shown in phantom lines in FIGS. 1, 7, 13 and 16 is for illustrative purposes only and forms no part of the claimed design.
